UNITED STATES PATENT OFFICE.

ANDRÉ COZE, OF REIMS, FRANCE.

GAS-RETORT BENCH.

SPECIFICATION forming part of Letters Patent No. 358,953, dated September 4, 1883.

Application filed June 25, 1887. Serial No. 242,454. (No model.) Patented in France February 14, 1885, No. 167,044; in Germany March 27, 1885, No. 33,959; in Belgium June 17, 1885, No. 69,316; in England June 20, 1885, No. 7,563; in Italy June 30, 1885, XXXVI, 438; in Austria-Hungary October 30, 1885, No. 23,286 and No. 57,022, and in Spain December 22, 1885, CXC, 7,837.

To all whom it may concern:

Be it known that I, ANDRÉ COZE, of the city of Reims, France, actually in Paris, have invented new and useful Improvements in Retorts for the Distillation of Coal and other Solid Matters, (for which I have obtained Letters Patent in France, No. 167,044, dated February 14, 1885; in Germany, No. 33,959, dated March 27, 1885; in Austria-Hungary, No. 23,286 and No. 57,022, dated October 30, 1885; in Spain, No. 7,837, folio 190^a, dated December 22, 1885; in Italy, No. 438, folio 36, dated June 30, 1885; in Belgium, No. 69,316, dated June 17, 1885, and in England, No. 7,563, dated June 20, 1885,) of which the following is a full, clear, and exact description.

This invention relates to improved retorts used for distilling coal and other solid matters.

20 The object of the present invention is to effect the charging and discharging of retorts by utilizing for the purpose the phenomenon known as the "angle of repose." To this end the retort, having a movable retaining-plate near its discharge end, is placed at such an inclination that the natural fall of the coal supplied at its highest end shall be sufficient to cause its distribution in a uniform layer throughout the whole length of the retort and 25 parallel with the bottom thereof. The retort is in this manner automatically charged, and owing to its inclination the coke, if slightly loosened from its sides and the retaining-plate moved, will slide downward without difficulty, 30 and thus also effect the automatic discharge of said retort.

The invention further consists in the details of improvement that are more fully herein-after set forth.

40 Reference is to be had to the accompanying drawings, forming part of this specification, it being understood that the invention is not limited to the exact arrangements shown, as they may be varied to suit different kinds of 45 furnaces, the number of retorts, &c.

Figure 1 is a vertical section of a bench of seven retorts, and Fig. 2 a sectional plan of the same. Fig. 3 is a transverse vertical section taken through the charging-chutes.

The same letters of reference represent the 50 same parts in the three figures.

a are the retorts, which are placed at an inclination approximating to that of the angle of repose of the matters with which they are to be charged, or, in other words, an inclination almost verging on the limit at which the matters to be distilled would commence to slide. This inclination is represented in the example shown as twenty-nine degrees; but it is evident that this angle may be varied to 55 suit the nature and smoothness of the interior of the retort, the size of the lumps of coal, &c. One end of each retort is provided with a charging-mouth, *b*, which is carried up vertically outside the furnace and closed by a cover, *c*. 60 Each chute is connected to its retort by a bend, so as to form a prolongation thereof, and the impact produced by the fall of the material around the bend, aided by the inclination given to the retort, produces a suitable 65 distribution of the matters in a layer of uniform thickness, without entirely filling the retort—that is to say, the plane of its surface is about 70 parallel with the floor of the retort, which is the most favorable condition for distillation, 75 as it leaves sufficient space in the retort to allow of the gases freely disengaging, and enables the distillation to be carried on under the ordinary conditions, as when the retorts are charged horizontally. The charging of 80 each retort is in this manner instantly effected.

d is a sight-hole or prolongation of the retort, closed by a double cover to enable the bend of the retort to be cleared in the event 85 of obstruction. The charging chutes are enclosed in a sand bath in order to maintain them at a suitable temperature and prevent any condensation therein. The arrest of the coal at the lower end of the retort may be effected either by means of a removable stop-plate, *e'*, fitting in grooves *e* and supported by a leg, *e''*, or as hereinabove described in connection with Fig. 15. By utilizing the angle of repose, which permits but a slow passage 90 of material, each particle of coal as it is arrested acts to hold the others in check, thereby preventing the retort becoming filled and 95

permitting the distribution of the coal in a uniform layer, as stated.

The ascension-pipes *f* and hydraulic main *g* are, in this example, of the ordinary kind; 5 but they may be otherwise arranged, as hereinafter described. As shown, the retaining-plate *e* does not extend entirely across the retort, thereby leaving a passage for gases to the main *g*.
 10 A single line of rails laid above the level of the retort-setting, as shown in the drawings, suffices for the supply of two oppositely-arranged benches of retorts, the contents of the truck *h* being discharged into each chute by 15 tilting it. The above arrangements may, however, be varied—as, for example, the charging-orifices may be all in the same horizontal plane, and the bends in the retorts be dispensed with by simply prolonging the retorts 20 until they reach the charging-level, which may be either inside or outside the furnace-setting, the retorts being either of the same or different lengths. As the degree of inclination given to the retorts is nearly equal to that 25 which would cause the material it contains to slide, it will be understood that it is simply necessary to impart the slightest possible movement to the lumps at the front end of the retort in order to insure the automatic dis- 30 charge of the coke into a wheelbarrow, *i*.

The invention, being entirely independent of the oven, may be applied to all kinds of coke-ovens and forms of retorts by merely modifying the details to suit each particular case.

35 The following relates to arrangements which may be employed according to circumstances for charging the retort parallel with its floor. These arrangements show various forms of retort-charging mouths and various forms of lids 40 for the charging-mouths as well as for the discharging ends of the retorts, which lids, however, form no part of the invention.

Fig. 4 shows the charging-mouths arranged to permit of the escape of the gas produced 45 into a hydraulic main, *g*, common to both benches of retorts. In this case the gas enters the hydraulic main through the charging-spouts *b* instead of through the roof of the retort, as ordinarily. In this manner a more 50 rational action is obtained, and the space which is usually occupied by the ascension-pipes in front of the retort is economized, while the same hydraulic main serves for both benches. Fig. 5 shows a hopper fixed above 55 the charging-mouth, a space being left between them to allow of a lid being applied. Fig. 6 shows the charging-mouth carried up to a level with a truck, *h*, said mouth being pro-

vided with a hinged cover, *c*, which is clamped by a screw-and-lever catch and suitably luted. 60 Fig. 7 shows a cover fitting in a groove filled with sand. Fig. 8 shows a cover clamped by means of a screw stirrup-piece hinged to the mouth of the retort. Fig. 9 shows the retort-mouths arranged in rows one above the other. 65 Fig. 10 shows a funnel-shaped mouth inclined at an angle to meet a truck when tilted. Fig. 11 shows other forms of charging-mouths brought to a uniform level. Fig. 12 shows a hopper movable in front of the charging- 70 mouths of the retorts. Fig. 13 shows a charging-mouth fixed upon a curve-ended retort, the retorts varying in length according to their position. Fig. 14 shows a series of fixed hoppers for enabling one or more retorts to be 75 charged at one time. The hoppers are each closed at bottom by a slide, *a*, by opening which the coal is allowed to fall into the charging-mouths *b*. A space is left between the hoppers and the charging-mouths. The retorts may be charged by trucks that run upon rails above the rails, as shown in Fig. 1, or by other suitable means. Said retorts may also be discharged in any suitable manner. Fig. 15 represents a section of the front or lower 80 end of a retort-bench in which the hydraulic main is set back beyond the front line of the retort-setting for the purpose of economizing space.

The upper retort is provided with lid *c*, to 90 which is attached the stop or retaining-plate *e*. The middle retort is shown as provided with a cast-iron retaining-plate, *e*, hooked to lugs cast on the head of the retort. The mid-rib is provided with an opening to admit of its removal. The lower retort is provided with a retaining-plate, *e*, of sheet-iron of **U** form, 95 with handles at either side, which is fixed in position by jamming against the sides of the retort-mouth. 100

I claim—

The inclined retorts *a*, placed one above the other, combined with the charging-mouths *b*, whose open ends are all on the same level, whereby the retorts may be charged from 105 trucks on the same level, substantially as set forth.

The foregoing specification of my improvements in retorts for the distillation of coal and other solid matters and in apparatus connected therewith signed by me this 14th day of May, 1887.

ANDRÉ COZE.
